UNITED STATES PATENT OFFICE

156,275

DESIGN FOR A COMBINATION TABLE AND CABINET

Lewis Pizzarelli, Poughkeepsie, N. Y.

Application June 4, 1948, Serial No. 146,753

Term of patent 7 years

(Cl. D33—19)

To all whom it may concern:

Be it known that I, Lewis Pizzarelli, a citizen of the United States, residing at Poughkeepsie, in the county of Dutchess and State of New York, have invented a new, original, and ornamental Design for a Combination Table and Cabinet, of which the following is a specification, reference being had to the accompanying drawings, forming a part thereof.

Figure 1 is a perspective view of the combination table and cabinet, showing the front, top, base and one end, the opposite end being like that illustrated.

I claim:

The ornamental design for a combination table and cabinet, as shown and described.

LEWIS PIZZARELLI.
